Attorneys.

UNITED STATES PATENT OFFICE.

ROBERT B. TAYLOR, OF CLEVELAND, OHIO, ASSIGNOR TO UNION CARBIDE & CARBON RESEARCH LABORATORIES, INC., A CORPORATION OF NEW YORK.

SHUNT CONNECTION.

Application filed March 28, 1922. Serial No. 547,447.

To all whom it may concern:

Be it known that I, ROBERT B. TAYLOR, a citizen of the United States, residing at Cleveland, in the county of Cuyahoga and 5 State of Ohio, have invented certain new and useful Improvements in Shunt Connections, of which the following is a specification.

This invention relates to means for attaching 10 flexible electrical conductors to current-receiving elements. More particularly, the invention comprises an improved construction adapted to connect shunts or cables to the brushes of dynamo-electric machines.

15 In accordance with prior practice, shunts may be attached to brushes by drilling an opening therein of somewhat larger diameter than the shunt, inserting an end of the shunt in the opening, and compacting a conductive material about the shunt to hold it in 20 position. The lateral engagement of the compacted material with the walls of the opening is alone depended upon to maintain the connection. To secure an adequate 25 engagement of this kind, it is necessary to tamp the material with considerable force, resulting in frequent breakage, especially when relatively soft and frangible brushes are used.

30 In the preferred embodiment of the present invention, an improved tamped connection is provided by anchoring a metal sleeve in an opening in the brush and compacting the conductive material about the end 35 of the shunt inserted in the sleeve.

The invention will be described in connection with the accompanying drawing, in which

Fig. 1 is a side elevation of a brush, broken 40 away to show the improved connection in vertical section,

Fig. 2 is a perspective view of one form 45 of the metal sleeve to be anchored in the brush,

Fig. 3 is a vertical section through a modified form of connection, and

Fig. 4 is a side elevation, broken away to show plate retaining means for one-cable 50 brushes.

Referring to Figs. 1 and 2 of the drawings, numeral 1 denotes a brush having a bore 2 adjacent one side and extending downwardly, preferably at an angle, from the top of the brush. An angle of 15° to the perpendicular through the center of the brush is preferred. The bore is widened at its bottom to provide a recess 3, which will in general be elliptical with its longer axis approximately parallel to the wider faces of the brush. However, recesses of circular 60 or any other suitable conformation may be provided. The recess may be easily formed by using a drill having a short cutting head mounted on a stem of less diameter. When the proper depth is reached, the drill is 65 shifted laterally and rotated to undercut the wall of the bore.

A metal thimble 4, cut away laterally as shown in Fig. 2, is inserted in the bore, and an outturned marginal flange 5 sustains the 70 thimble with its base above the recess 3. A plate 6 of metal or other suitable material, adapted to be engaged by pressure-applying means for forcing the brush against the commutator, may be provided. The plate 75 6 is perforated at 7 to permit the passage of thimble 4 and the outturned flange 5, overlying the plate, retains it in position. The plate may carry a finger piece 8 for lifting the brush. 80

The thimble 4 is anchored in the brush by embedding its lower end in a molten or plastic material 9 adapted to solidify into a strong, coherent mass. I prefer to use type metal in this connection. The metal is 85 melted and poured into the bore 2 in amount sufficient to fill the recess 3 and the lower portion of the bore. On cooling, the metal expands very slightly, thus insuring close engagement and good electrical contact with 90 the thimble and the wall of the bore. The solidified metal body is incapable of upward displacement, owing to its engagement in the enlargement at the bottom of the bore. The thimble is securely anchored in or linked 95 to the metal body by its end being embedded therein, and is therefore effectively retained.

Instead of type metal, I may use other alloys. These should in general have a fairly high melting point, to prevent softening should the brush become hot, and they should not contract much on solidifying. Phenolic condensation products may also be used to anchor the thimble in the brush.

A shunt 10 of somewhat smaller diameter than the thimble is inserted therein, with its end adjacent the anchoring material 9. A conductive, cementing composition 11 is then tamped between the shunt and thimble. The composition 11 is preferably copper amalgam, and may be of the kind described in Patent No. 1,199,635 granted to H. B. Eynon, of June 27, 1916. However, the invention is not limited to any particular conductive cement.

The cementing composition 11 in plastic condition is forced into close contact with the thimble 4 and the wall of the opening in the brush. The composition hardens into a block having a shoulder 12 engaging ring 13 at the head of the thimble. In this manner greater security against loosening and displacement of the cementing composition is obtained than when only the lateral engagement of the cement is effective. A braided conductor or cable will ordinarily be used. The surface irregularities of such conductors are entered by the plastic, which upon solidifying securely binds the conductor in the desired position.

In the form of the device illustrated in Fig. 3, the thimble is replaced by a tubular rivet having one end 15 expanded into recess 3. The end of a shunt 10 is then inserted in the rivet and a conductive cementing material 11 tamped in. The rivet may be cut away as at 16.

Fig. 4 illustrates means for securing a plate upon the brush when only one cable connection is desired. A recessed bore 2 and thimble 4, of the type described, are provided, and a rivet 17 is inserted in the thimble. The rivet has a head 18, overlying flange 5, and an enlarged lower end 19, which is embedded in type metal or other suitable cementing material 20. In this manner the rivet is securely linked to the immovable cementing body in the bore and retains that end of the plate 6 which is not held by the connection carrying shunt 10.

I have illustrated by way of example a carbon brush carrying two shunts, 10 and 10', and having a pressure plate 6 and finger piece 8 through which force to press the brush against its coating surface, or to remove it from said surface, may be applied. While the structure described herein affords a simple and effective means for securing such force transmitting members, these members may of course be omitted when not required. One or more shunts may be at-

tached, as desired. The brush may consist of a metal alloy, metal-graphite composition, or other suitable material. The invention is particularly applicable, however, to relatively frangible carbon brushes, as the thimble or rivet protects the carbon from much of the disintegrative effect of the tamping pressure. In some cases I may use the same material as both thimble-anchoring and shunt-holding means. For example, type metal may be poured about the end of a shunt properly positioned in the thimble, or copper amalgam or the like may be tamped into the bore and recess so as to hold both the thimble and shunt in position. Various other modifications of the specific forms described herein may be made within the scope of the appended claims.

I claim:-

1. A conductive block having a bore therein, a conductor, a metal sleeve in said bore and adapted to receive a portion of said conductor, and means for securing the sleeve and conductor in the block.

2. The invention according to claim 1, in which one portion of the bore is recessed, and the sleeve is provided with means engaging the recessed portion, whereby movement of the sleeve along the bore is prevented.

3. A conductive block having a bore therein, a metal thimble adapted to fit into said bore and to receive a conductor, and means overlying a portion of the thimble and engaging the bore, whereby displacement of the thimble is prevented.

4. The invention according to claim 3, in which the bore is recessed adjacent its base, and a cementing material is filled into the bore and recess so as to embed the lower portion of the thimble.

5. The invention according to claim 4, in which the cementing material is type metal.

6. The invention according to claim 4, in which the conductor is secured in the thimble by a conductive, cementing material compacted between the thimble and conductor.

7. The invention according to claim 6, in which the cementing material has a shoulder abutting against a portion of the thimble.

8. A shunt connection for a brush having a bore therein, comprising a metal sleeve in said bore; means for securing said sleeve, a shunt having one end inserted in said sleeve, and a cementing material compacted about said shunt and retaining it in the sleeve.

9. A brush having an interior cavity, a bore of relatively small diameter connecting the cavity with a brush surface, a body of strong material larger than the bore and located within the cavity, and an anchoring element extending through the bore and linked with said body of strong material.

10. A brush having a bore therein, a plate upon one surface of said brush and having

a perforation overlying said bore, and a metal sleeve secured in said bore and having a flange overlying said plate.

11. A brush having an interior cavity, a bore of relatively small diameter connecting the cavity with a brush surface, a body of strong material larger than the bore and lo-

cated within the cavity, and a member adapted to transmit a force to the brush, said member being anchored through said bore 10 to the body of strong material.

In testimony whereof, I affix my signature.

ROBERT B. TAYLOR.
